(57) **CLAIM**

The ornamental design for a mouthguard container, as
shown and described.

DESCRIPTION

FIG. 1 illustrates a side view of a mouthguard container, showing my new design;

FIG. 2 illustrates a bottom perspective view thereof, shown
in partially closed condition;

FIG. 3 illustrates a bottom view thereof;

FIG. 4 illustrates a top perspective view thereof; and,
FIG. 5 illustrates a top perspective view thereof, shown in
closed condition.

The broken lines in the figures illustrate the portions of the
mouthguard container and form no part of the claimed
design.
